(57) **CLAIM**

The ornamental design for a rotary driving tool/trimmer, as shown and described.

DESCRIPTION

FIG. 1 is a front, right side and top perspective view of a rotary driving tool/trimmer, showing my new design;

FIG. 2 is a front, left side and top perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top end view thereof; and,

FIG. 8 is a bottom end view thereof.

No claim is made to the power cord shown in broken lines.

The broken line showing of the power cord forms no part of the claimed design.
